FOCUS SYSTEM

John De Leon, Ridgewood, N. J., assignor to Allen B. Du Mont Laboratories, Inc., Clifton, N. J., a corporation of Delaware

Application December 21, 1950, Serial No. 201,913

4 Claims. (Cl. 315—31)

1

This invention relates to magnetic apparatus for affecting electron beams and the like. The particular embodiment here described is a focus coil and electrical circuit for adjusting the focus of electron beams in cathode ray tubes.

An object of this invention is to provide an apparatus for adjusting focus coil current with improved efficiency.

Another object is to provide a focus adjusting circuit in which the circuit resistance does not change appreciably when the focus is adjusted.

A further object is to provide a circuit having a large range of focus adjustment.

Other objects will be apparent from the following disclosure.

In the drawings—

Figure 1 is an electrical circuit diagram of an embodiment of the invention;

Figure 2 is a diagrammatic representation of a focus coil construction; and

Figure 3 is a side view of the focus coil positioned on a cathode ray tube.

The focus coil 11 contains multiple turns of wire having an inner end terminal 12 and an outer end terminal 13. A tap terminal 14 electrically partitions the coil 11 into two parts comprising inner turns 16 and outer turns 17.

The focus coil 11 is connected in series with a fixed resistor 18, electronic circuits 19, and a voltage source 21. A focus control potentiometer 22 is connected between the tap terminal 14 and a junction 23 between the fixed resistor 18 and electronic circuits 19. The adjustable tap 24 of the potentiometer 22 is connected to the inner end terminal 12 of the focus coil 11. A magnetic core, not shown in the drawing, is generally employed to confine and distribute the focusing field.

Focus current is adjusted by means of the potentiometer 22. When the adjustable tap 24 is positioned at the end "a," the inner turns 16 are short circuited and current passes only through the outer turns 17 of the focus coil; this is the condition for a minimum focusing magnetic field (minimum ampere turns). To obtain the maximum focusing magnetic field (maximum ampere turns), the tap 24 is positioned at the end "b" of the potentiometer 22; a portion of the current then passes through the inner turns 16 and the entire current passes through the outer turns 17. The fixed resistor 18 functions to cause a more constant resistance of the focus circuit between the terminals 13 and 23 when the potentiometer is adjusted. The desideratum of more constant circuit resistance is also aided by the

2

connection of the potentiometer 22 across a portion of rather than the entire focus coil.

Other objects of the invention are accomplished by connecting the circuit to the focus coil in the manner shown and described, so that the focus control potentiometer 22 comprises a variable shunt resistance with respect to the inner turns 16, and does not affect the current in the outer turns 17. This manner of connection advantageously utilizes the fact that the outer turns 17 have a larger resistance than the inner turns 16 because the outer turns have a larger circumference and therefore greater resistance per turn.

15 By connecting the focus current adjusting control across a portion of focus coil turns having a relatively low ratio of resistance per turn, stabilization of circuit resistance is improved because a smaller change in the control resistance will suffice to provide a required change in ampere turns. Also, the range of focus adjustment is greater for a given change in the focus control resistance.

In the preferred embodiment shown, the focus coil tap 14 is located at a position between the resistive center and turn center of the coil. However, in some applications it might be desirable to locate the tap 14 at a different position.

It may, under certain conditions, be desirable to isolate electrically the inner turns from the outer turns, and to provide four terminals on the focus coil. The outer turns can then be connected to one source of current, and the inner turns can be connected to a source of adjustable current.

35 When designing a magnetic control circuit in accordance with the present invention, the following criteria may be considered:

1. Determine the required ampere turns for the outer turns 17 in accordance with the minimum required magnetic field.

2. Determine the required ampere turns for the inner turns 16 in accordance with the maximum required magnetic field, making allowance for the shunt current that will bypass through the potentiometer 22.

3. Determine the resistance of the potentiometer 22 as a compromise among: required wattage rating, maximum required magnetic field, linearity of control, and tolerable range of change in total circuit resistance.

4. Determine the value of the fixed resistance 18 to obtain optimum stability of total circuit resistance with respect to changes in focus adjustment.

Although the invention is described in detail for a particular application having electronic circuits connected in series therewith, it may also be connected in parallel to a power source.

The scope of the invention is defined in the following claims.

What is claimed is:

1. Apparatus for producing a controlled magnetic field, comprising a coil connected in a series circuit, said coil having multiple turns and two end terminals, a direct current source connected to one of said end terminals and across said circuit, a tap on said coil, and current adjusting means comprising variable resistance connected directly between said tap and the other of said end terminals.

2. An adjustable magnetic focus system for a cathode ray tube comprising a coil having an inner turn portion and an outer turn portion and a tap between said inner and outer turn portions, a fixed resistance element having one end connected to said inner turn portion, a potentiometer connected between said tap and the other end of said fixed resistance element, an adjustable tap on said potentiometer connected to said inner turn portion, and a current source connected to said outer turn portion.

3. In a television receiver, a cathode ray tube and a magnetic focus system associated therewith, said system comprising a coil positioned

5

with respect to said cathode ray tube, said coil having an inner turn portion and an outer turn portion and a tap between said inner and outer turn portions, a fixed resistance element having one end connected to said inner turn portion, a junction at the other end of said fixed resistance element, a potentiometer connected between said tap and said junction, an adjustable tap on said potentiometer connected to said inner turn portion, electronic circuits connected to said junction, and a voltage source connected between said electronic circuits and said outer turn portion of said coil.

4. An adjustable magnetic device comprising a coil having a tap thereon, a fixed resistance element having one end connected to an end of said coil, a potentiometer connected between said tap and the remaining end of said fixed resistance element, an adjustable tap on said potentiometer connected to said end of said coil, and a current source connected between the remaining end of said coil and said remaining end of said fixed resistance element.
